TYPEWRITING MACHINE

Jesse A. B. Smith, Stamford, Conn., assignor to
Underwood Elliott Fisher Company, New York,
N. Y., a corporation of Delaware

Application October 20, 1931. Serial No. 569,915

20 Claims. (Cl. 197—126)

This invention relates to work-holders and sheet-interleaving means for front-strike type-writing machines having round platens.

In my pending application No. 549,812, filed July 10, 1931, superposed carbon-sheets lie flat upon a work-table at the delivery side of the platen. A line of stitching connects the carbon-sheets at their lower ends. The work-sheets are inserted one under another edgewise and between the carbons as they lie upon the paper-shelf. The work-sheets rest upon the line of stitching.

Said stitching connects the carbons to a flexible binder-sheet, which extends from said table down around the front of the platen, and is gripped by the feed-rolls, the latter holding the carbons steady while the work-sheets are being inserted. Each work-sheet is thrust in between the carbons and merely dropped upon the stitches, and is thrust to the left to a side-gage.

20 The uppermost work-sheet overlies the uppermost carbon, and its lower edge is inserted under a tongue which extends up from the flexible binder-sheet.

An object of the present improvements is to provide for ready front-insertion of envelopes into the machine. This is done without having to remove the pack of carbons or subjecting them to wear.

The flexible binder-strip carries a transverse flap some distance below the aforesaid stitching. This flap receives the work-envelope, the flap being placed at a point sufficiently low so that the typing on the envelop does not reach up and overlap the carbons.

35 The binding trailer and envelop-carrier is reinforced at a point below the envelop, to save it from injury to prevent wrinkling and creasing when fed around the platen.

The binder-sheet is transversely doubled and 40 stitched across, so as to form an upwardly-directed tongue serving as the envelop-clip. The latter extends about half an inch above the line of stitching.

During typing of an envelop, the accompanying work-sheet, just typed, may lie flat upon the table, in sight of the operator. The operator may copy the envelop directly from the heading on the letter.

When the gathering table, which is adjustably 50 pivoted, is swung down to the rear of the machine, the carbon-set with its binding trailer or coupling-flap and its two clips may be inserted, top first, at the rear of the platen by the aid of the usual paper-table, in the same manner as an ordinary work-sheet. The platen is rotated, thus

bringing the carbons up in front and entirely above the platen. The interleaving table is then restored to its operative position, and the carbons recline against said gathering table behind and above the platen. Then the sheets are inserted, 60 and the platen is rotated backward to bring the pack into typing position.

When the work-sheet clip is about even with the lower edge of the gathering table, the envelop-clip projects somewhat above the usual front wing-scale, so that the operator may easily thrust an envelop down in said clip, to rest upon the row of binding stitches. The platen may now rotate backwardly to bring the envelop to typing position.

Another feature is that the backing-sheet projects slightly beyond the right-hand side-edge of the carbon-sheets, to facilitate the interleaving of work-sheets between said carbons.

The gathering table is mounted upon the non-shiftable carriage-frame of the machine, and is preferably hinged behind the platen upon said carriage-frame, so that it can be moved to a position back of the typewriter. The hinged table is locked in either position.

70 Said table is provided with a pair of left-hand sheet-gathering gages, which may be adjusted across the table, and is also provided with a centering-scale marked at its bottom, to facilitate the centering of the heading of the letters to be 75 manifolded.

Other features and advantages will herein-after appear.

In the accompanying drawings,

Figure 1 is a perspective view of the platen 90 and associated parts of a typewriting machine having the invention applied thereto. This view shows the carbon-set element lying flat upon the gathering table during typing of an envelop caught in the auxiliary envelop-clip of the driving flap of said carbon-set.

Figure 2 is a plan view showing diagrammatically the gaging of a work-sheet against the left-hand truing gage.

Figure 3 is a sectional view on line 3—3 of 100 Figure 5, showing a detail of the gathering table.

Figure 4 is a front view showing diagrammatically how the centering-scale is used.

Figure 5 is a sectional side-view showing the front-insertion of the envelop into the auxiliary 105 clip.

Fig. 6 shows in perspective the carbon-set element with the novel envelop-clip applied thereto.

Figure 7 is a sectional side-view showing the 110

pack of carbon-sheets and interleaved work-sheets in printing position around the platen.

Figure 8 is a sectional detail view showing the upper side-gage.

Carbon-sheets 10 are stitched at their bottom edge to a backing-sheet 11, together with the upper end of a binding trailer or flap 12, so as to form an upper work-sheet clip or tab 13 above the line of stitching 14 (Figure 6).

- 10 The right-hand upper corners of the carbons 10 are cut off and graded so as to form overlapping lips or margins 15, acting as guides for facilitating the interleaving of the work-sheet. A cutaway 16 is likewise made in the backing-sheet 11 for simultaneous withdrawal of the typed sheets by grasping the corners thereof left exposed by said cutaway 16.
- 15

- 10 The right-hand edge of the backing-sheet 11 projects beyond the corresponding edge of the carbons 10 so as to form a right margin 17 facilitating the interleaving and gaging of the work-sheets, as will be more completely described hereinafter.

- 15 The lower part of the binding trailer 12 is transversely folded at 18 and is stitched to itself at 19 so as to form above the lower transverse line of stitching 19 an upwardly projecting tongue or border 20 and a doubled trailing or coupling reinforced portion 21 under said lower line of stitching. This reinforced lower portion 21 of the binding trailer 12 is made wider on both sides of the carbon-set to accommodate envelopes wider than the work-sheet. The shoulders 22 thus formed, as well as the overlapping ends of the tongue 20, are preferably rounded to prevent their catching the paper-fingers of the machine. It will be noted that the shoulders 22 which may be spaced above the top of the tongue 20 form with said top a graduated page-end indicator co-operative with the wing-scale 30 to indicate when the typing is approaching the bottom of a work-piece held by the tongue 20.

- 20 By first swinging a sheet-gathering table 31 rearwardly to the vertical position shown in dotted lines at Figure 5, the operator may insert the described carbon-set containing any desired number of carbon-sheets 10 downwardly (top first) at the back of a platen 23 over a paper-table 24 until its upper edge engages rear feed-rolls 25. The platen 23 is then rotated by means of one of the usual knobs 26 fastened at both ends of a platen-shaft 27 to feed said carbon-set into the feeding path formed around the front part of said platen, said carbon-set being guided by an arcuate apron 28 forming a continuation of the paper-table 24, front feed-rolls 29 and the usual wing-scale 30.

- 25 When the envelop-clip 20 emerges from the wing-scale 30 and reaches in front of the printing line, its normal position, shown in Figure 5, the operator stops this rotation of the platen, lifts the table 31 to the position shown in full line in Figure 1, and throws back upon said table the carbon-sheets 10 and their backing 11, which recline in front of the platen over the keyboard of the machine. The carbon-set now lies flat on the gathering table with its work-sheet clip 13 about even with the lower edge of the gathering table 31 and ready for interleaving the work-sheets 32 to be manifolded.

- 30 As shown in Figure 5, in this position the doubled part 21 of the trailer or flap 12 is still gripped between the platen and the feed-rolls 25, 29, thus establishing a mechanical coupling 75 between the carbon-set and said platen and in-

suring the parallelism of the stitching-lines 14, 19, and therefore of the clips 13, 20, with the platen-axis.

The feed-rolls 25, 29 now co-operate with the trailer or flap 12 to hold the carbons 10 steady on the gathering table 31, while blank work-sheets 32 are inserted edgewise one by one to interleave with said stationary carbons 10, as described in my said co-pending application Serial No. 549,812. The bottom edges of said work-sheets descend first to a line of rest upon the row of binding stitches 14, and the sheets are then gathered against a pair of side-gage plates 33, 34, arranged at the left-hand side of the interleaving table 31. This gathering operation is done merely by pressing the sheets to the left as far as they will go with the aid of the margin 17 which prevents the interference with the right edges of the carbons.

The right-hand side of the table 31 is clear for 95 the operator's hand.

The last blank work-sheet 32 is placed upon the uppermost carbon 10 with its lower edge caught and clipped by the work-sheet clip 13.

When the work-sheets 32 have been interleaved with the stationary carbons 10, the platen is rotated backwardly in the usual manner to pull the manifolding pack thus formed down into the machine into position for the typing of the first line thereon.

The usual swingable center paper-finger 35 is then swung in operative position to deflect the top edge of said pack back against the platen, so that it will fall down by gravity on the gathering table 31, as it is progressively brought back 110 upon said latter to its initial position by the line-spacing operations. The backing-sheet 11 is, though flexible, sufficiently stiff to insure that the pack will automatically bridge the gap existing between the lower edge of the table 31 and 115 the top of the platen (as shown in Figure 7).

To aid the operator in centering the heading of the letter to be manifolded, a rear scale 36 is marked on the lower edge of the gathering table 31.

120 After typing, the paper-finger 35 is released and the manifolding pack is run further up by rotating the knob 26 until it reaches the position shown in Figure 5, in which the upper work-sheet clip 13 is about even with the lower edge of the gathering table 31, while the lower envelop-clip 20 emerges above the wing-scale 30, and the lower line of stitches 19 is still engaged behind said wing-scale.

130 In this position the operator may easily insert in front of the platen an envelop 37 down into said clip 20 until the bottom edge of said envelop rests upon the stitching-line 19, the top edge of the wing-scale aiding to clamp said bottom edge of the envelop in said clip 20.

135 The platen is now rotated backwardly to bring said envelop to typing position, the envelop being preferably held against the platen by means of the paper-finger 35.

140 The heading of the letter typed, readable on the top work-sheet 32, is thus brought down on the table 31 nearer the platen and well in sight of the operator, who has then merely to copy the address to be typed on said heading, as shown in Figure 1.

145 After typing of said envelop, the operator releases the paper-finger 35, withdraws the envelop and grasps the upper right-hand corners of the typed work-sheets 32 between her thumb and her forefinger, and withdraws them from the 150

carbon-set by one stroke of her hand, due to the cutaway 16, provided in the backing-sheet 11.

This easy and rapid removal of the work-sheet leaves the carbon-sheets in their normal position assembled and flat upon the gathering table 31, ready to receive a new set of blanks.

The platen-shaft 27 is journaled in two end-plates 38 forming with cross-bars and operating levers (not shown) the shiftable platen-frame 10 of the machine.

To avoid increasing the weight and momentum of said shiftable platen-frame which would result from mounting the gathering table 31 directly thereon, said table is mounted instead on the 15 non-shiftable carriage-frame 39, which is slidably mounted by means of guides 40 on the usual rails 41.

To mount the table 31 upon said carriage-frame, use is made of two brackets 42, fastened 20 to the cross-bar 39 under the paper-table 24 by means of screws 43, and projecting to the rear of said paper-table.

The board forming the table 31 is provided with two lateral downwardly-projecting flanges 44, a 25 top flange 45, and a bottom flange 46, on which is marked the scale 36. These flanges serve as reinforcing ribs, suppress the sharp edges of the table, and give to the same a neat appearance.

Integral with the two lateral flanges 44 are 30 two downwardly-projecting ears 47 which are pivotally mounted between and in abutting relation with said brackets 42 on two collar-screws 48. In a circular opening 49 of the left-hand side bracket 42 is riveted or otherwise fastened 35 a socket 50, in which is guided the rod or stem 51 of a plunger 52. This rod 51 projects inwardly so as to form a cylindrical lug 53 and outwardly to carry an operating knob 54. This lug 53 co-operates with two holes 55 and 56 provided in the left-hand ear 47 to hold the table 31 either in its operative position, in which it is 40 substantially tangent to the platen, or in its vertical position (shown in dotted line in Figure 5). A spring 57 is mounted on the rod 51 within the 45 socket 50 to hold the lug 53 engaged in either of said holes 55, 56.

The lateral flanges 44 of the table 31 are furthermore provided at each end with ears 58, in 50 which are mounted two fixed rods 59, lying under the table close and parallel to the top and bottom edges thereof. Each of said rods has on its under side a longitudinal groove or keyway 60, co-operating with key-projections 61 formed in ears 62 upturned on each side of the 55 resilient arcuate portion 63 of each side-gage 33, 34, in order to prevent rotation of said ears 62 about the rods 59. The arcuate portion 63 of each gage 33, 34 acts as a spring to press the bottom or body-portion 64 of the gage against the 60 upper face of the table 31, while said ears 62 act as slides to guide the gages along the rods 59 when it is desired to adjust said gages in position across the table. Springs 65, having U-shaped profile, are mounted upon the rods 59, 65 between and in abutting relation with the ears 62 of each gage 33, 34, so as to press against said rods and to hold the gages in their adjusted position.

When it is not desired to use the gathering and interleaving table, the plunger 52 may be easily pulled out so as to unlock the table 31, and this latter may be then swung downwardly in its 70 abased position (shown in dotted line in Figure 11), back of the typewriter for convenience in

dropping said latter into the usual typewriter-desk.

Variations may be resorted to within the scope of the invention, and portions of the improvements may be used without others.

Having thus described my invention, I claim:

1. In a front-strike typewriting machine, the combination with a revoluble platen, of work-sheet gathering and manifolding means including as an element a set of carbon-sheets fastened together at their lower ends to a flap extending downwardly below said lower carbon-sheet ends and permanently coupled to the platen and including as another element a gathering board for supporting a work-sheet in flat condition, said board being disposed to support at the delivery side of the platen the pack of carbon-sheets and inserted work-sheets, said coupling flap being arranged to receive and hold while still retained around the platen the lower edge of an extra work-piece for typing thereon without interfering with the carbon-sheets and the work-sheets therebetween, said carbon-sheets and work-sheets resting on said gathering board during the insertion and the typing of said extra work-piece. 100

2. In a typewriting machine, the combination with a revoluble platen, of a work-sheet-gathering table extending upwardly and rearwardly from said platen and provided with an adjustable side-gage for gathering the work-sheets at their 105 sides, a manifolding device for facilitating the interleaving of the work-sheets with a carbon-sheet lying flat upon said table during said interleaving and also subsequently to the typing of said work-sheets, a trailer connected to the bottom of the carbon-sheet and permanently coupled to the platen, and an envelop front-insertion device formed on said trailer and allowing a ready 110 typing of envelopes without having to remove the carbon-set from the machine and without wear- 115 ing out the carbon-sheet.

3. In a typewriting machine, the combination, with a revoluble platen, and paper-feeding means co-operating with said platen, of a work-sheet gathering table extending upwardly and rear- 120 wardly from said platen and provided with an adjustable sheet-gathering side-gage, a manifolding device facilitating the interleaving of work-sheets with a carbon-sheet lying normally flat upon said table, a binding trailer or flap permanently coupling the carbon-sheet to said paper-feeding means, a work-sheet clip extending upwardly from the top of said binding-trailer over the lower end of the carbon-sheet and serving as gage and carrier for the uppermost work- 125 sheet, and an envelop front-insertion device arranged on said binding-trailer below said clip. 130

4. In a typewriting machine, the combination with a stationary frame, a carriage reciprocating on said frame, a platen-frame shiftable mounted 135 on said carriage, a revoluble platen journaled in said shiftable frame, a wing-scale secured to said stationary frame, and paper-feeding means co-operating with said platen, of a work-sheet-gathering table hinged to said carriage behind 140 said platen, and releasably held in operative position in which it is tangentially inclined with respect to the delivery generatrix of said platen, a manifolding device including a carbon-sheet normally held flat upon said table and coupled to said 145 paper-feeding means by a trailer, and an envelop front-insertion device arranged on said trailer below the bottom of the carbon-sheet and co-operating with said wing-scale.

5. In a typewriting machine, the combination 150

- with a revoluble platen, paper-feeding means co-operating with said platen, and a work-sheet gathering table extending upwardly and rearwardly from said platen and provided with an 5 adjustable sheet-gathering side-gage, of a manifolding device facilitating the interleaving of work-sheets with a carbon-sheet lying normally flat upon said table, a binding trailer or flap permanently coupling said carbon-sheet to said 10 paper-feeding means, a work-sheet clip extending upwardly from the top of said binding-trailer over the lower end of the carbon-sheet and serving as gage and carrier for the uppermost work-sheet, and an auxiliary envelop-clip extending 15 across said binding-trailer at a distance below said work-sheet clip at a sufficient distance to prevent the typing on the envelop from overlapping the carbon-sheet.
6. In a typewriting machine having a revoluble 20 platen, paper-feeding means co-operating with said platen, and also having a sheet-gathering table extending upwardly and rearwardly from said platen and provided with an adjustable sheet-gathering side-gage; a manifolding device facilitating the interleaving of work-sheets with a 25 carbon-sheet lying normally flat upon said table, a binding trailer or flap permanently coupling said carbon-sheet to said paper-feeding means, a work-sheet clip extending upwardly from the 30 top of said binding-trailer over the lower end of the carbon-sheet and serving as gage and carrier for the uppermost work-sheet, and an auxiliary envelop-clip extending across said binding-trailer at a distance sufficiently below said work-sheet 35 clip to prevent the typing on the envelop from overlapping the carbon-sheet, said envelop-clip being made wider than said carbon-sheet to accommodate envelopes wider than the work-sheet, said envelop-clip never coming within range of 40 said gathering side-gage.
7. As an article of manufacture, a manifolding carbon-set for use in typewriting machines comprising, in combination, a carbon-sheet, a 45 flexible backing-sheet carrying said carbon-sheet and giving body to the carbon-sheet and adjacent work-sheets, a binding-trailer or driving-flap fixed to the lower end of said carbon-sheet so that the upper end of said binding-trailer forms a work-sheet clip, and an auxiliary work-piece 50 clip extending across said binding-trailer at a distance below said work-sheet clip to receive and hold an extra work-piece for typing thereon without interfering with the other work or carbon-sheets.
- 55 8. As an article of manufacture, a manifolding carbon-set for use in typewriting machines comprising, in combination, a carbon-sheet, a flexible backing-sheet carrying said carbon-sheet and projecting slightly beyond the right-hand 60 side thereof to facilitate the interleaving of work-sheets therewith, a binding-trailer or driving-flap fixed to the lower end of said carbon-set, so that the upper end of said binding-trailer forms a work-sheet clip, and an auxiliary work-piece 65 clip extending across said binding-trailer at a distance below said work-sheet clip to receive and hold an extra work-piece for typing thereon without interfering with the other work or carbon sheets.
- 70 9. As an article of manufacture, a manifolding carbon-set for use in typewriting machines comprising, in combination, a carbon-sheet, a flexible 75 backing-sheet, and a binding-trailer or driving-flap, a line of stiches joining the bottom of said carbon-sheet and of said backing-sheet to the top of said binding-trailer and serving as a work-sheet bottom truing gage, a work-sheet clip being formed by a part of said binding-trailer projecting above said stitching-line, said binding-trailer being folded and doubled on a transverse line constituting the lower end of said trailer and being line-stitched to itself so as to form above the stitching-line a tongue serving as an envelop-clip below the work-sheet clip, the latter stitching-line forming an envelop truing gage, and the doubled trailer forming a reinforced driving-flap. 80
10. Apparatus for the purpose specified including a carbon-sheet and a flap stitched to the carbon-sheet at the lower end of the latter, said flap extending up above the stitching to form a front upper clip to receive the lower margin of the front work-sheet and extending down from said stitching to form an envelop-carrier provided with a front lower clip spaced below the upper clip to receive the lower edge of an envelop. 85
11. Apparatus for the purpose specified including a carbon-sheet and a flap to which the carbon-sheet is stitched at its lower end, said flap extending up above the stitching to form a front 100 upper clip to receive the lower margin of the front work-sheet and extending down from said stitching to form a driving-trailer, the lower part of which is doubled and stitched to itself to form a front lower clip below the upper clip to receive 105 the lower edge of an envelop.
12. In a manifolding carbon-set including a carbon-sheet for use in a typewriting machine, a driving trailer for coupling said carbon-sheet to the paper-feeding means of said machine, and 110 an envelop-clip facilitating the front-insertion into the machine and the typing of an envelop directly after typing and manifolding of a letter, and without having to withdraw said carbon-set and said typed letter from the machine, said 115 clip being substantially below the lower end of the carbon-sheet and formed on said trailer.
13. In a manifolding carbon-set including a carbon-sheet for use in a typewriting machine, a driving-trailer for coupling said carbon-sheet to 120 the paper-feeding means of said machine, and an envelop-clip facilitating the front-insertion into the machine and the typing of an envelop directly after typing and manifolding of a letter, and without having to withdraw said carbon-set 125 and said typed letter from the machine, said envelop-clip being substantially below the lower end of the carbon-sheet and being formed by a tongue of said driving-trailer projecting above a stitching-line which extends over the entire 130 width of said driving-trailer, so as to form a full-length envelop bottom-gage and make a flat structure not liable to hit the paper-guiding means of the machine.
14. In a typewriting machine having a platen, 135 the combination, with a work-sheet gathering table, of a manifolding carbon-set including a trailer permanently coupled to the platen, and means associated with said trailer and located between the lower end of the latter and the carbon for front-inserting, clipping, gaging and facilitating the typing of an envelop, without having to withdraw said carbon-set from the machine and before removing from said table the manifolded letter just typed, the letter and carbon-set resting on said table during typing of the envelop. 140
15. In a typewriting machine having a platen, the combination with a work-sheet-gathering table, of a manifolding carbon-set including a 145

- trailer permanently coupled to the platen, and means associated with said trailer and disposed between the lower end of the latter and the carbon-set for front-inserting, clipping, gaging and facilitating the typing of an envelop, without having to withdraw said carbon-set from the machine and before removing from said table the mani-folded letter just typed, said letter and the carbon resting on the table so that the heading of said letter is in sight of the operator, thereby exhibiting the address to be typed on the envelop. 5 80
16. For use in a typewriting machine having a platen and bottom feed-rolls co-operating therewith; a flexible work-piece-holding element feedable longitudinally around the platen, said element having a transverse fold whereby said element is doubled forwardly upon itself at its lower portion, the outer ply extending part way up said element and being fastened on a transverse line 15 90 to the rear ply, the plies extending substantially above the fastening line to form a work-piece-holding clip, the doubled portion of said element below said line constituting a trailer or flap whereby said element is retained by means of the feed-rolls while typing down to the bottom margin of a work-piece held in said clip. 20 95
17. For use in a typewriting machine having a platen and bottom feed-rolls co-operating therewith; a flexible work-piece-holding element feedable longitudinally around the platen, said element having a transverse fold whereby said element is doubled forwardly upon itself at its lower portion, the outer ply extending part way up said element and being fastened on a transverse line 25 100 to the rear ply, the plies extending substantially above the fastening line to form a work-piece-holding clip, the doubled portion of said element below said line constituting a trailer or flap whereby said element is retained by means of the feed-rolls while typing down to the bottom margin of a work-piece held in said clip, the rear ply extending above said clip to form a backing for the work-piece. 30 105
18. For use in a typewriting machine having a platen and bottom feed-rolls co-operating therewith; a flexible work-piece-holding element feedable longitudinally around the platen, said element having a transverse fold whereby said element is doubled forwardly upon itself at its lower portion, the outer ply extending part way up said element and being fastened on a transverse line 35 110 to the rear ply, the plies extending substantially above the fastening line to form a work-piece-holding clip, the doubled portion of said element below said line constituting a trailer or flap whereby said element is retained by means of the feed-rolls while typing down to the bottom margin of a work-piece held in said clip, the rear ply extending above said clip to form a backing for the work-piece. 40 115
19. For use in a typewriting machine having a platen and bottom feed-rolls co-operating therewith; a flexible work-piece-holding element feedable longitudinally around the platen, said element having a transverse fold whereby said element is doubled forwardly upon itself at its lower portion, the outer ply extending part way up said element and being fastened on a transverse line 45 120 to the rear ply, the plies extending substantially above the fastening line to form a work-piece-holding clip, the doubled portion of said element below said line constituting a trailer or flap whereby said element is retained by means of the feed-rolls while typing down to the bottom margin of a work-piece held in said clip, the rear ply extending above said clip to form a backing for the work-piece, the trailer being wider on each side than said backing, the widened lower portion of said element beginning at a point substantially above the top of the clip on each side of said element. 50 125
20. For use in a typewriting machine having a platen and bottom feed-rolls co-operating therewith; a flexible work-piece-holding element feedable longitudinally around the platen, said element having a transverse fold whereby said element is doubled forwardly upon itself at its lower portion, the outer ply extending part way up said element and being fastened on a transverse line 55 130 to the rear ply, the plies extending substantially above the fastening line to form a work-piece-holding clip, the doubled portion of said element below said line constituting a trailer or flap whereby said element is retained by means of the feed-rolls while typing down to the bottom margin of a work-piece held in said clip, the rear ply extending above said clip to form a backing for the work-piece, the trailer being wider on each side than said backing, the widened lower portion of said element beginning at a point substantially above the top of the clip on each side of said element, the inner and outer corners at the shoulders being rounded to facilitate the passage of the element between the feed-rolls and the platen. 60 135

JESSE A. B. SMITH.
